BRUSH HOLDER

Richard Bauerle, Pittsburgh, Pa.

Application May 18, 1938, Serial No. 208,691

6 Claims. (Cl. 248—113)

This invention relates to an improved brush holder and is especially designed to support a previously used paint brush in a receptacle so the bristles are immersed in a bath of oil or the like to prevent hardening.

The primary object of the invention is to provide a simple form of brush holder that may be supported across the open top of a liquid containing receptacle and which automatically grips the brush handle when so positioned.

Another object of the invention is to provide a brush holder that will support various size brushes.

Still another object of the invention is to provide a brush holder that is a separate article of manufacture, automatically engageable with the brush to be suspended in the liquid by the act of positioning and supporting the holder across the top of the liquid containing receptacle.

A further object of the invention is to provide an arrangement whereby a plurality of the brush-engaged holders may be supported across the top of the liquid containing receptacle.

A still further object of the invention is to provide a very simple and economical form of brush holder which may be manufactured and sold as a separate unit.

Other objects will, from the description, be apparent to those skilled in the art. The present disclosure constitutes an exposition of an embodiment of the invention, and illustrates the best means I have thus far devised for reducing the invention to practice. It is to be understood that the structural details shown and described shall not constitute limitations inconsistent with the scope of the invention as claimed.

In the drawing:

Figure 1 is a perspective view showing a pair of brushes supported by my improved holder across the top of an open top receptacle;

Figure 2 is a side elevation of the holder in closed position;

Figure 3 is a vertical section through the holder in open or brush-engaging position;

Figure 4 is a top plan view of the holder in open position with an engaged brush handle shown in section;

Figure 5 is a vertical section on the line 5—5 of Figure 3.

The brush holder is preferably manufactured as a unitary article preferably formed of aluminum or sheet metal and comprises a pair of arms 1 and 2 of substantially identical construction. Each arm has a top portion 3 with depending side walls 4 tapering toward one end thereof. The

extremities of the side portions form projecting ears 5 which are connected by transverse pivot studs 6. This pivotally connects the arms 1 and 2 so they may be swung vertically from the position shown in Figure 2 to the position shown in 5 the other figures of the drawing.

The ends of the arms adjacent the pivots form gripping or clamping jaws 7 and 8 on the edges thereof, adapted to engage a paint brush handle B therebetween. These jaws diverge from the 10 pivotal connections as shown in Figure 3, and terminate in medially disposed opposed V-shaped notches 9 in which the brush handle B is clamped.

The outer end of the arm 1 may be provided with an angularly bent lip 10, while the outer end 15 of the arm 2 may have formed thereon an eye 11 for a purpose to be hereinafter more fully described.

In use when the holder is positioned as shown in Figure 2, by a slight spreading of the arms 1 20 and 2 the arms may slide down over a paint brush handle, the handle passing easily through the open jaws 7 and 8. The arms are then swung to horizontal or gripping position whereby the opposed jaws will move toward each other and grip 25 the shank of the brush handle at any desired point between the V-shaped notches 9. Resting the outer end portions of the arms 1 and 2 on any suitable support, such as opposite edges of an 30 open top receptacle, will suspend the brush at any desired height therein. Generally these holders are used in connection with a receptacle containing oil or the like in which the bristle portion of the brush is immersed to prevent hardening of the bristles after use. By the act of sliding my 35 holder over the handle portion of a brush and then swinging vertically or expanding the arms so they may rest on the edge of an open top receptacle or the like, the shank of the brush handle is automatically clamped between the opposed jaws in a manner that will be obvious. This will suspend the brush so the bristles may be held immersed in the liquid.

A most important feature of my invention is the adaptability of this holder to grip and hold 45 different sized brushes. The gripping jaws 7 and 8 diverge from the pivots as clearly shown in Figure 3. Thus, there is provided a range of bite between the opposed jaws that compensates for the varying diameters of the handles of different size brushes. For the average size brush, the arms are supported substantially horizontally for clamping the handle. For larger or smaller brush handles, there is an inclination above or below the horizontal respectively for gripping action.

Quite often it is desired to support or hold a plurality of brushes in a liquid containing receptacle. As in such instances the open top receptacle is of a greater diameter than the expanded 5 length of my holder, I have provided means for accomplishing this purpose as illustrated in Figure 1. The numeral 12 designates an open top receptacle having an upper edge 13. Across the edge is positioned a rod 14. To support plural 10 holders across the top of the receptacle, the rod 14 is passed through the eyes 11 on the outer ends of the arms 2 while the bent lips 10 of the arms 1 lap over the receptacle edge 13. In the form shown only two brushes are supported in 15 the receptacle 12, but within limits any number may be supported therein by this means.

My invention is especially designed for supporting paint brushes in an open top receptacle, but the holder as a support may be applied to 20 various other uses. Essentially the invention comprises a holder surrounding and slidable on the brush handle in one position and automatically gripping the same when moved to and supported in another position. In the plural use 25 closed, the receptacle may be of any desired shape permitting the necessary suspension of the holders across the top of the receptacle.

What I claim is:

- 30 1. A paint brush holder comprising a pair of sheet metal arms having tapering side portions terminating in forwardly extending ears, pivots connecting said ears, and the forward edges of said arms adjacent the pivots being inclined rearwardly therefrom.
- 35 2. A paint brush holder comprising a pair of sheet metal arms having tapering side portions terminating in forwardly extending ears, pivots connecting said ears, the forward edges of said arms adjacent the pivots being inclined rear-

wardly therefrom, an eye formed on the opposite end of one of said arms, and a lip formed on the opposite end of the other of said arms.

3. As an article of manufacture a foldable paint brush holder comprising a pair of arms hingedly engaging each other at one end and adapted to slide over a paint brush handle in non-gripping position, and the engaged ends of said arms forming gripping jaws engageable with the handle when the arms are swung outwardly 10 to gripping position.

4. As an article of manufacture a foldable paint brush holder comprising a pair of arms hingedly engaging each other at one end and adapted to slide over a paint brush handle when 15 disposed in substantially parallel relationship and to engage the same adjacent the medial hinge when extended, and the handle engaging ends of said arms being inclined away from the hinge to grip various sized handles therebetween. 20

5. As an article of manufacture a foldable paint brush holder including a pair of sheet metal arms each comprising a top with depending side walls hingedly engaging each other at one end and the adjacent ends of each top being 25 spaced from the pivots to form opposed gripping jaws having a variable range of engagement to support different sized brushes therebetween.

6. As an article of manufacture a brush holder of the class described for associating with an 30 open top receptacle of a certain diameter comprising a pair of horizontally extending pivotally connected arms adapted to support and surround and grip a paint brush handle between the pivoted ends thereof, said arms when extended being less than the diameter of the receptacle, and means to support a plurality of said holders across the open top of the receptacle. 35
